UNITED STATES PATENT OFFICE.

ELBERT L. COUCH, OF HARTFORD, CONNECTICUT, ASSIGNOR TO SILVEREASE COMPANY INC.

APPARATUS FOR CLEANING ARTICLES.

1,083,992.

Specification of Letters Patent. Patented Jan. 13, 1914.

Application filed November 19, 1912. Serial No. 732,211.

To all whom it may concern:

Be it known that I, ELBERT L. COUCH, a citizen of the United States, residing at 275 Homestead avenue, Hartford, in the 5 county of Hartford and State of Connecticut, have invented certain new and useful Improvements in Apparatus for Cleaning Articles, of which the following is a specification.

10 The object of my invention is to provide a device of a class specified, which has features of novelty and advantage.

Figure 1 is a perspective view of the various parts of the apparatus. Fig. 2 is a 15 section of the apparatus showing the various parts in the positions which they occupy when in use. Fig. 3 is a perspective view of the plate which is used in the receptacle.

This apparatus is to be used in connection with a solution for cleaning diamonds, 20 glass, and various metals, such as gold, nickel, brass, copper, etc., and particularly tarnished silver. It is generally employed in connection with the solution (a mixture 25 compounded by mixing carbonate of soda and carbonate of calcium in the proportion of 11 parts, by weight, of calcium to one part of soda and to each ounce of this mixture adding two quarts of water) claimed 30 in Letters-Patent No. 674,254 "Processes of cleaning silver", in which it is stated that this solution is to be used in a "proper" receptacle. This proper receptacle I find, 35 after many years of experiment, to be most advantageously made in the following way: The receptacle 1 may be of any material. I also use a basket or drainer 2, which may be of any material and made in any manner suitable for the purpose. I use a plate 3 in 40 the bottom of the receptacle. It may be placed either in the basket 2, or underneath, or in any other position, as convenience dictates, and the articles to be cleaned 7 are then put in the basket and immersed in the 45 solution. It is essential that there be a metallic connection between the plate and the articles to be cleaned either by placing them in engagement with each other or by using a metallic basket, or in any other desirable 50 manner. With that exception their relative positions in the solution are immaterial.

It is convenient at times, when it is desired to use the plate inside the basket, to have said plate constructed with the flange 55 4, which surrounds it with the exception

that it is discontinued at each of the notches 6. This construction raises the plate somewhat from the bottom of the basket, and allows the same to be drained more easily.

It is found that when silver or other metals are immersed in this solution the tarnish is removed by electrolysis or chemical action, or in some other manner, and is deposited on the plate. After the apparatus has been used a number of times, the plate 65 becomes oxidized and tarnished, the plate being one electrode, called usually the anode, and the articles to be cleaned the other, and thus a coating is formed over the plate which therefore becomes less active. It is 70 for this reason that I find it more convenient to use a removable plate in order that it may be readily cleaned. This plate I have constructed of various materials, and especially of aluminum, tin, lead, antimony, 75 and other metals. I find however from experiment that more than one of these metals may be used to advantage in various partial or complete combinations. The preferable combination is as follows:— 80 aluminum 40%, tin 40%, lead 10% and antimony 10%, these proportions being at times more or less varied. I produce this combination in its best form by fusing these metals, although they may be combined in any 85 other manner. This combination produces the most satisfactory results for the following reasons:—I find that tin will give a satisfactory chemical or electrical action and produce results, but I find further that aluminum combined with the tin gives a much more rapid action, and will cause action to take place in the solution at a lower temperature than that where tin is used alone. The lead in the combination closes the pores 90 and makes the mass more smooth and homogeneous, thus preventing the tarnish from penetrating into the plate, and for this reason making it more easy to clean. The addition of antimony strengthens and hardens the plate, thus prolonging its life. Any of these metals may be omitted, or one or more combined in any particular form.

I prefer to use this apparatus in the way described above with the receptacle, plate 105 and basket. The drainer, basket or inner receptacle may be composed of any material whatsoever so long as it is constructed sufficiently open to permit of the solution after immersion to be rapidly drained when the 110

basket, drainer, or inner receptacle is lifted out of the solution, and at the same time sufficiently closed that the articles to be cleaned cannot pass or drop through the meshes or openings; but I have found the most practical basket or drainer to be one made of perforated metal. I do not however wish to confine myself to that particular method alone. Many variations of this apparatus are possible. I find however that it is preferable to use the apparatus as described above, having the receptacle and basket made of material which will not receive the tarnished coating, the plate alone being oxidized or tarnished, the plate being easily cleaned. I find as one variation that the plate may be made of any substance, plated or coated with the above mentioned combination, and of course this same method may be applied to the receptacle and basket where they are used without the plate.

Claims:

1. In an apparatus for cleaning articles, an anode in the form of a plate forming one electrode and formed of a fused combination embodying tin and lead, for use in connection with an electrolytic solution and articles to be cleaned, the said articles forming the other electrode.
2. Apparatus for cleaning articles comprising a receptacle to be used in connection with electrolytic solution and articles to be

cleaned, a plate, said plate forming one electrode and the articles to be cleaned the other said plate being a fused combination embodying tin and lead. 35

3. Apparatus for cleaning tarnished articles, comprising a receptacle of a material which will not receive the tarnished coating and an anode composed of aluminum, tin, 40 lead, and antimony.

4. Apparatus for cleaning tarnished articles, comprising a receptacle and an anode composed of aluminum 40%, tin 40%, lead 10%, and antimony 10%. 45

5. Apparatus for cleaning tarnished silver, comprising a receptacle, an electrolytic solution, a plate, said plate being the anode, and the articles to be cleaned the cathode, said plate being a fused combination of aluminum 40%, tin 40%, lead 10%, antimony 10%. 50

6. In an apparatus for cleaning articles, an anode forming one electrode and formed of a combination of aluminum, tin, lead and 55 antimony for use in connection with electrolytic solution and articles to be cleaned, said articles forming the other electrode.

In testimony whereof I affix my signature in presence of two witnesses.

ELBERT L. COUCH.
